[57] CLAIM

The ornamental design for a table, as shown and described.

DESCRIPTION

FIG. 1 is a perspective view of a table showing my new design;

FIG. 2 is a front plan view thereof, the rear being a mirror image of the side shown;

FIG. 3 is a top plan view thereof; and,

FIG. 4 is a side plan view thereof, the opposite side being a mirror image of the side shown.
